CLAIM

The ornamental design for a tray, as shown and described.

DESCRIPTION

FIG. 1 is a top, front perspective view of a tray in accordance with our new design;

FIG. 2 is a bottom, rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The broken lines in the figures show portions of the tray that form no part of the claimed design. The dash-dot lines in FIGS. 1-8 define the bounds of the claimed design. The claimed design extends to but does not include the defined boundary.
